UNITED STATES PATENT OFFICE.

FRANK S. TUCKER AND FRED M. LAXTON, OF CHARLOTTE, NORTH CAROLINA.

SHOE-HEEL PROTECTOR.

1,081,412.

Specification of Letters Patent. Patented Dec. 16, 1913.

Application filed April 25, 1911. Serial No. 623,262.

To all whom it may concern:

Be it known that we, FRANK S. TUCKER and FRED M. LAXTON, citizens of the United States, residing at Charlotte, in the county 5 of Mecklenburg and State of North Carolina, have invented certain new and useful Improvements in Shoe-Heel Protectors, of which the following is a specification.

The object of our invention is to produce 10 a shoe heel protector consisting of an anti-slip and anti-noise insert for treads, comprising metals of different degrees of hardness and resonance and arranged in parallel relation.

15 It is desirable in devices of this character to not only provide a wear resisting surface in treads, but to provide in combination therewith, a means for reducing the noise incident to impact.

20 In the drawing, Figure 1 is a bottom plan view of an insert for a tread embodying our invention; Fig. 2 is a vertical central section of the same; Fig. 3 is a vertical central section of a slightly modified construction; Fig. 4 is a top plan view of another embodiment of our invention; Fig. 5 is a vertical central section of the same; Fig. 6 is a vertical central section of another embodiment of our invention; Fig. 7 is a 25 central vertical section of still another embodiment of our invention; Fig. 8 is a bottom plan view of a heel of a shoe prepared to receive the insert; Fig. 9 is a vertical central section of another embodiment 30 of our invention; and Fig. 10 is still another embodiment of our invention.

1 represents a shell constructed of any suitable hard wear resisting metal, such for instance as steel, said shell being preferably 40 cylindical in cross section and tapered at the top as at 2, the top of the shell being closed by an end 3 as shown in Fig. 3. As shown in Fig. 7, the shell may be provided with a barb 4 for the purpose of 45 more securely anchoring the shell in its inserted position; while in Fig. 5, we have

shown the top of a shell provided with a flat, more or less flexible securing element 5. In the construction shown in Figs. 4 and 5, 50 it will be noticed that the outer periphery of the shell is cut away, as at 6, providing a recess between the securing element 5 and a shoulder 7 on the shell, into which the material of the tread may flow or be inserted, so as to provide a further locking means against the inward accidental dis-

placement of the insert whereby the outer edge of the insert is maintained in proper alignment with the wearing face of the heel.

In Fig. 6, we have illustrated the upper 60 end of the shell as being provided with an annular enlargement 7 and a recess 8, which coöperate with the collar 9 to lock the insert in position.

The shell in each instance is filled with a 65 soft non-resonant metal 3^a, such as lead or an alloy, which is swaged into holding contact with the steel shell, so that there is no danger of its becoming accidentally displaced from the shell.

We are aware that wear resisting inserts 70 for treads consisting of steel or other hard metal and of steel and iron have been used, but these are objectionable in that the steel inserts become smooth, thus increasing the 75 liability of slipping, besides which, they do not absorb the noise incident to impact. The inserts consisting of steel and soft iron 80 are objectionable in that they become highly polished, thus increasing the tendency of slipping besides which, they do not absorb the noise incident to impact on the tread.

By the use of our invention on treads, we 85 not only reduce the liability of slipping, but we are enabled to absorb practically all of the noise due to impact, thus producing in one and the same device, an anti-slip and anti-noise insert for treads.

The constructions shown are equally well 90 adapted for leather treads and rubber treads. In rubber treads, it would perhaps be better to mold the insert shown in Figs. 4, 5, 6 and 7, in the tread as the tread is being formed. In molding the insert in a rubber heel, the top of the insert and the locking medium are positioned in such relative 95 position with respect to the upper and lower faces of the heel that the insert is cushioned on the upper portion of the body of the heel so that the cushioning effect of a rubber 100 heel is not destroyed in the use of our invention.

In inserting the inserts, for instance, those shown in Figs. 1, 2, 3 and 7, it is our practice to drill a hole in the tread, of a diameter 105 to insure a neat driving fit between the outer wall of the shell and the wall of the hole in the tread—the friction between the shell and tread, due to the snug driving fit, being sufficient to hold the insert against accidental displacement. In the construction shown in Fig. 7, the barb 4, would, as will be

readily understood, bite in the walls of the opening in the tread.

While we have selected the heel of a shoe for the purpose of illustrating the invention, 5 it will, of course, be understood that the insert is adapted for use in connection with treads in general.

The word "lead" in the claims will be understood to be sufficient to include not 10 only lead, but other metals and alloys which are non-resonant.

In the embodiment shown in Fig. 9, 10 is a steel tube in which a lead packing 11 is swaged, the lead packing having an enlarged head 12 which overlaps the upper 15 edge of the steel tube 10, thus providing a packing of lead for the steel tube, which constitutes a shock absorber. In Fig. 10, 13 is a steel or other hard metal tube in which is swaged a lead plug 14 provided 20 with an annular flange 15 at its top, said flange projecting beyond the perimeter of

the tube 13. This form of plug is more especially adapted to be used with a rubber heel, the flange 15 acting as a lock around 25 which the rubber heel may be molded. In these two constructions, the lead will be spread when hammered in, and provide means for holding the plug in the shoe.

We claim:—

30 An anti slip and noise insert for treads, comprising a steel tube and a lead insert in said tube flush with one end of the tube and having an annular flange overhanging the other end of the tube and constituting a 35 packing for the said tube.

In testimony whereof we affix our signatures in presence of two witnesses.

FRANK S. TUCKER.
FRED M. LAXTON.
